(57) **CLAIM**

The ornamental design for a pedicure basin base, as shown and described.

DESCRIPTION

FIG. 1 is an upper front perspective view of the pedicure basin base according to my design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof, a left side view being a mirror image thereof; and,

FIG. 7 is a rear bottom perspective view thereof.

1 Claim, 7 Drawing Sheets
